UNITED STATES PATENT OFFICE.

WILLIAM A. PIKE, OF PITTSFIELD, MASSACHUSETTS, ASSIGNOR TO EATON, CRANE & PIKE COMPANY, OF PITTSFIELD, MASSACHUSETTS, A CORPORATION OF MAINE.

DESIGN FOR A DISPLAY-CARD.

52,405.

Specification for Design. Patented Sept. 10, 1918.

Application filed April 24, 1917. Serial No. 164,289. Term of patent 7 years.

To all whom it may concern:

Be it known that I, WILLIAM A. PIKE, a citizen of the United States of America, residing at Pittsfield, in the county of Berkshire and State of Massachusetts, have invented a new, original, and ornamental Design for Display-Cards, of which the following is a specification, reference being had to the accompanying drawings, forming part thereof.

Figures 1 and 2 are face and side views,

respectively, of a display card, showing my new design. The dotted lines on Fig. 1 indicate one arrangement of writing paper and envelop upon the card.

I claim:—

The ornamental design for a display card, as shown.

In witness whereof, I have hereunto signed my name.

WILLIAM A. PIKE.
